CLAIM

The ornamental design for an annular blade, as shown and described.

DESCRIPTION

FIG. 1 is a top perspective view of an annular blade in accordance to a first embodiment in the context of an exemplary rotary knife;

FIG. 2 is a top perspective view of the annular blade independent of the exemplary rotary knife;

FIG. 3 is a bottom perspective view thereof;

FIG. 4 is a top plan view thereof;

FIG. 5 is bottom plan view thereof;

FIG. 6 is a front elevation thereof;

FIG. 7 is a rear elevation view thereof;

FIG. 8 is a side elevation view thereof; and

FIG. 9 is a cross-sectional view thereof taken along line 9-9 in FIG. 4.

FIG. 10 is a top perspective view of an annular blade showing my new design in accordance to another embodiment in the context of an exemplary rotary knife;

FIG. 11 is a top perspective view of the annular blade independent of the exemplary rotary knife

FIG. 12 is a bottom perspective view thereof;

FIG. 13 is a top plan view thereof;

FIG. 14 is bottom plan view thereof;

FIG. 15 is a front elevation view thereof;

FIG. 16 is a rear elevation view thereof;

FIG. 17 is a side elevation view thereof; and

FIG. 18 is a cross-sectional view along line 18-18 of FIG. 13.

FIG. 19 is a cross-sectional view along line 19-19 in FIG. 10.

FIG. 20 is a top perspective view of an annular blade in accordance to a another embodiment in the context of an exemplary rotary knife;

FIG. 21 is a top perspective view of the annular blade independent of the exemplary rotary knife;

FIG. 22 is a bottom perspective view thereof;

FIG. 23 is a top plan view thereof;

FIG. 24 is bottom plan view thereof;

FIG. 25 is a front elevation view thereof;

FIG. 26 is a rear elevation view thereof;

FIG. 27 is a side elevation view thereof; and

FIG. 28 is a cross-sectional view along line 28-28 in FIG. 23.

FIG. 29 is a cross-sectional view along line 29-29 in FIG. 20

FIG. 30 is a top perspective view of an annular blade in accordance to another embodiment in the context of an exemplary rotary knife;

FIG. 31 is a top perspective view of the annular blade independent of the exemplary rotary knife;

FIG. 32 is a bottom perspective view thereof;

FIG. 33 is a top plan view thereof;

FIG. 34 is bottom plan view thereof;

FIG. 35 is a front elevation view thereof;

FIG. 36 is a rear elevation view thereof;

FIG. 37 is a side elevation view thereof;

FIG. 38 is a cross-sectional view along line 38-38 in FIG. 33; and

FIG. 39 is a cross-sectional view along line 39-39 in FIG. 30.

FIG. 40 is a top perspective view of an annular blade in accordance to another embodiment in the context of an exemplary rotary knife;

FIG. 41 is a top perspective view of the annular blade independent of the exemplary rotary knife;

FIG. 42 is a bottom perspective view thereof;

FIG. 43 is a top plan view thereof;

FIG. 44 is bottom plan view thereof;

FIG. 45 is a front elevation view thereof;

FIG. 46 is a rear elevation view thereof;

FIG. 47 is a side elevation view thereof; and,

FIG. 48 is a cross-sectional view along line 48-48 in FIG. 43.

The broken line showing of the rotary knife is provided for the purpose of illustrating environmental structure and forms no part of the claimed design.
